UNITED STATES PATENT OFFICE.

CARL J. BARTON, OF BIG RAPIDS, MICHIGAN.

GAS-MANTLE SUPPORT.

No. 898,957.

Specification of Letters Patent. Patented Sept. 15, 1908.

Application filed March 30, 1908. Serial No. 424,031.

To all whom it may concern:

Be it known that I, CARL J. BARTON, a citizen of the United States, residing at Big Rapids, in the county of Mecosta and State of Michigan, have invented an Improvement in Gas-Mantle Supports, of which the following is a specification.

As is well-known, the so-called gas mantles attached to gas burners for intensifying the brilliancy of the flame, are very brittle and liable to be cracked or broken off when jarred or otherwise set suddenly in vibration. To avoid this result, and thus prolong the "life" of such mantles, I have devised an improved means for supporting them from a burner.

The invention also includes an improved construction and combination of parts whereby I provide for convenient attachment of the mantle support to a burner and detachment of the same therefrom, the support being held firmly on the burner while in use.

The construction and combination of parts embodying the invention as a whole are hereinafter described, and the novel features specifically indicated in the claims.

In the accompanying drawing, Figure 1 is a side view showing my improved attachment for a pendent burner, the parts being inclosed in a glass globe which is shown partly broken away. Fig. 2 is an enlarged horizontal section on the line 2—2 of Fig. 1. Fig. 3 is a cross section on the line 3—3 of Fig. 2. Fig. 4 is a perspective view—part being broken away—of my improved mantle support.

In the several figures of the drawing, A indicates the mantle proper, B the support therefor, and C a pendent burner to which the support is applied. The mantle may be constructed in the usual manner and of the usual materials; and its top edge is attached at 1, to the inner ring 2, of the support B. This ring is pivoted at opposite points 3, to a ring 4, and the latter is in turn pivoted at opposite points 5 to an outer ring 6. It will be noted that the pivotal points 5 are arranged 90° from the pivots 3 of the inner or mantle ring. Thus the support B, so far as described, is practically identical with the well-known gimbal commonly employed for supporting a ship's compass, and for various other purposes when it is desirable to provide for vibration or swinging of a suspended object in any direction. The inner or mantle ring 2 is formed of burnt clay, and the

outer ring 6 is constructed of the same material. In other words, these two rings are practically constructed of porcelain, while the middle or intervening ring 3 is formed of plate metal. A distinguished feature of the outer ring is the provision of integral prongs or arms 7 that extend upward and then inward, the same being three in number and their ends converging to a common center, but separated by a distance slightly exceeding the diameter of the upper portion 8, of the burner C. Such part 8 is provided with vertical grooves 9 in which the inner ends of the arms, or prongs, 7 are adapted to slide up or down, and between the grooves 9 are thickened or enlarged portions having recesses 10 in their upper edges for holding the ends of the arms 7. As shown in Figs. 1 and 2, the mantle support has been applied to the burner C by sliding the inner ends of the arms 7 upward in the three correspondingly vertical grooves 9, and then rotating the support a fraction of a circle, or until, the said arms drop into the recesses 10, when they are held from lateral movement. Thus the outer porcelain ring of the gimbal support B is held firmly or immovably in horizontal position, while the metal ring 3 is free to move or swing in a vertical plane, as is also the inner porcelain mantle ring 2.

It will be apparent by the construction, arrangement, and combination of parts above described, that the pendent mantle A is suspended in such manner that it may rock or vibrate freely in any direction laterally, which enables it to successfully resist jars or sudden movements of the burner from any cause, so that it is not liable to be cracked or broken as when suspended immovably. It is further apparent that by means of the support B, constructed as shown and described, the whole attachment may be easily applied to and quickly removed from a burner and that it is nevertheless held firmly in the required horizontal position when in place as indicated in Fig. 1.

What I claim is:

1. The combination, with an inverted burner having its body provided with vertical grooves and intervening thickened portions having recesses in their upper edges, of a metal mantle-support comprising rings pivoted together to form a gimbal, or universal joint, the outer ring having inwardly projecting convergent arms adapted to slide upward in the grooves of the burner and to

seat on the recessed portions of the same, substantially as described.

2. The combination, with a pendent burner, of a gas mantle and support therefor, the latter comprising parts forming a universal joint that allows the mantle proper to rock laterally in any direction, the outer portion of such joint having projections that engage the burner detachably, as shown and described.

3. The improved gas-mantle support comprising an inner ring and a surrounding ring which are pivoted together at opposite points, and a third or outer ring to which the intermediate ring is also pivoted so as to form a universal joint, the outer ring being constructed with inwardly projecting convergent arms, adapted for attachment to a burner, substantially as described.

4. The improved gas-mantle support, comprising three rings which are pivoted together to form a gimbal and the outer ring provided with devices adapted for detachable engagement with a pendent burner, substantially as described.

5. The improved gas-mantle support comprising an outer porcelain ring provided with integral, inwardly projecting and convergent horizontal arms, an inner porcelain ring to which the mantle is, in practice, attached, and a third intervening ring which is pivoted both to the inner and outer ones, substantially as described.

CARL J. BARTON.
